Primary Examiner — Michelle E. Wilson*Assistant Examiner* — Clese Moore, Jr.(74) *Attorney, Agent, or Firm* — Perkins IP Law Group LLC; Jefferson Perkins(57) **CLAIM**

We claim an ornamental design for a hitch step, as shown and described.

DESCRIPTION

FIG. 1 is a top rear right perspective view of a hitch step according to our design;

FIG. 2 is a top front left perspective view of our design;

FIG. 3 is a front view of our design;

FIG. 4 is a left view of our design, a right view being a mirror image of the left view;

FIG. 5 is a top view of our design; and,

FIG. 6 is a rear view of our design.

The broken lines shown illustrate environment that forms no part of the claimed design. The bottom surface of the hitch step is unadorned and forms no portion of the claimed design.

1 Claim, 4 Drawing Sheets(56)
